UNITED STATES PATENT OFFICE.

LAUREN S. BEARDSLEY, OF NAUGATUCK, CONNECTICUT.

DESIGN FOR AN INSULATOR-HOLDER.

SPECIFICATION forming part of Design No. 24,191, dated April 9, 1895.

Application filed January 12, 1895. Serial No. 534,715. Term of patent 7 years.

To all whom it may concern:

Be it known that I, LAUREN S. BEARDSLEY, a citizen of the United States, residing at Naugatuck, in the county of New Haven and State of Connecticut, have invented a certain new and useful Design for Insulator-Holders, of which the following is a full, clear, and exact description.

My new and original design has reference to holders for insulators for electric wires.

In the accompanying drawings Figure 1 is a side elevation of an insulator holder made according to my design. Fig. 2 is a front view of the same.

The said holder has an outer stem portion A which is spirally grooved at one end a and to the other end of which joins the curved

arm B. The end of the arm B opposite to the stem A is expanded and through this expanded part there is formed a hole D.

C represents a portion which projects beyond the expanded end of the curved arm B and between which and the arm there is formed a disk or plate E.

What I claim is—

The design for an insulator holder, substantially as shown and described.

In testimony whereof I have hereunto affixed my signature, in the presence of two witnesses, this 31st day of December, 1894.

LAUREN S. BEARDSLEY.

Witnesses:

HENRY P. McCARTHY,
FRANK J. CONRAN.
